COVER FOR CASSEROLE OR SIMILAR ARTICLE

R. Guy Cowan, Fayetteville, N. Y., assignor to Onondaga Pottery Company, Syracuse, N. Y., a corporation of New York

Application July 13, 1950, Serial No. 11,136

Term of patent 14 years

(Cl. D44—15)

To all whom it may concern:

Be it known that I, R. Guy Cowan, a citizen of the United States, residing at Fayetteville, State of New York, have invented a new, original, and ornamental Design for Cover for Casserole or Similar Article, of which the following is a specification, reference being had to the accompanying drawing, forming a part hereof.

The dominant feature of the design resides in the handle having at each end a pronounced upturned curlicue in combination with the six groups of the surface ornamentation as shown in cross section Figure 2, equally spaced and radiating from the axis of the cover from a point adjacent the handle to a point adjacent the periphery of the cover as shown.

I claim:
The ornamental design for a cover for casserole or similar article, as shown and described.

R. GUY COWAN.
